US0D1016571S

(12) **United States Design Patent** (10) **Patent No.:** **US D1,016,571 S**
(45) **Date of Patent:** **** Mar. 5, 2024**

(54) **VACUUM FOOD STORAGE CONTAINER**

(71) Applicant: **TAIZHOU JUMA TECHNOLOGY CO., LTD**, Taizhou (CN)

(72) Inventor: **Shanhao Jin**, Yizheng (CN)

(73) Assignee: **TAIZHOU JUMA TECHNOLOGY CO., LTD**, Taizhou (CN)

(**) Term: **15 Years**

(21) Appl. No.: **29/798,431**

(22) Filed: **Jul. 8, 2021**

(30) **Foreign Application Priority Data**

Jan. 19, 2021 (CN) 202130035435.0

(57) **CLAIM**

The ornamental design for a vacuum food storage container, as shown and described.

DESCRIPTION

FIG. 1 is a perspective view of a vacuum food storage container showing my new design;

FIG. 2 is a front view thereof, a rear view being identical to the front view;

FIG. 3 is a left side view thereof, a right side view being identical to the left side view;

FIG. 4 is a top view thereof; and,

FIG. 5 is a bottom view thereof.

The broken lines depict portions of the vacuum food storage container that form no part of the claimed design.

1 Claim, 5 Drawing Sheets
